CLAIM

I claim the ornamental appearance for AN fitting bracket, as shown and described.

DESCRIPTION

FIG. 1 is a top perspective view of AN fitting bracket;
FIG. 2 is a front view thereof;
FIG. 3 is a top view thereof;
FIG. 4 is a right side view thereof;
FIG. 5 is a left side view thereof;
FIG. 6 is a back view thereof;
FIG. 7 is bottom view thereof; and,
FIG. 8 is a bottom perspective view thereof.
The broken lines represent environment and form no part of the claim.
